UNITED STATES PATENT OFFICE.

ASHLEY C. SMITH, OF CHICAGO, ILLINOIS.

MILL.

SPECIFICATION forming part of Letters Patent No. 687,275, dated November 26, 1901.

Application filed January 30, 1901. Serial No. 45,297. (No model.)

To all whom it may concern:

Be it known that I, ASHLEY C. SMITH, a citizen of the United States, residing at Chicago, in the county of Cook and State of Illinois, have invented certain new and useful Improvements in Mills, of which the following is a specification.

This invention relates to improvements in that class of mills used for crushing and grinding corn in the ear; and it consists in certain peculiarities of the construction, novel arrangement, and operation of the various parts thereof, as will be hereinafter more fully set forth and specifically claimed.

15 The principal object of my invention is to provide a portable mill which shall be so constructed that it will first crush the corn in the ear or while the grain is on the cob and will then convey the crushed material to suitable burs for grinding the same, from whence the ground material may be automatically conveyed and passed through other burs for reducing the material to finer particles.

Another object of the invention is to so construct the mill that one set of said burs may be used for grinding small grain, so that when it is desired it may be mixed with the crushed corn and cobs without passing the smaller grain through the first set of burs.

30 A further object of the invention is to provide a simple and efficient means for the adjustment of the burs with respect to one another.

Still another object is to so construct the burs that they will be self-cleaning, thus preventing any of the crushed material clinging to or clogging them at their peripheries.

Other objects and advantages of the invention will be disclosed in the subjoined description and explanation.

In order to enable others skilled in the art to which my invention pertains to make and use the same, I will now proceed to describe it, referring to the accompanying drawings, 45 in which—

Figure 1 is a view in side elevation of a mill embodying my invention. Fig. 2 is a plan view thereof. Fig. 3 is a vertical longitudinal sectional view, taken on line 3 3 of Fig. 2, 50 looking in the direction indicated by the arrows, and showing the crushing and grinding mechanism on an enlarged scale. Fig. 4 is an enlarged cross-sectional view, taken on line 4 4 of Fig. 3, looking in the direction in- dicated by the arrows; and Fig. 5 is a perspective view of a portion of one of the burs, showing it provided with a cleaning-finger.

Similar letters refer to like parts throughout the different views of the drawings.

A represents the main or supporting frame, 60 which may be made of any suitable size, form, and material, and on which is horizontally journaled in suitable bearings a main or driving shaft B and an auxiliary shaft C, which are parallel with one another. Around 65 the shaft B is a cylinder D, which is provided in its upper portion with an opening d, with which communicates one end of an inclined hopper E, used for conveying the ears of corn or other material to be crushed and ground 70 to the interior of the circular or cylindrical portion D, which surrounds a portion of the shaft B, to which power may be applied for operating the mill. One end of the cylinder D is provided with an external flange d', to 75 which is secured by means of bolts d² or otherwise a bur F, which is serrated on its outer surface and has a central opening f, through which the crushed material may pass. The bur F is preferably provided with an annular 80 recess f' on its outer surface for the reception and operation of the cleaning-fingers g, with which the rotatable bur G is provided. One end of the shaft B is screw-threaded and provided with a series of indentations or niches 85 b, which are arranged spirally around the said screw-threaded portion, as is clearly shown in Fig. 3 of the drawings.

Mounted on the shaft B near its screw-threaded end is a gear H, which is prevented 90 from turning thereon by means of a key or feather h, which also engages the hub of an overhanging pulley H', which is preferably provided with a balance-wheel H² on the inner portion of its periphery. Located on the 95 screw-threaded portion of the shaft B is a nut h', which is provided with a set-screw h² to engage the depressions b in the shaft. Fixed on the shaft B within the cylinder D is a sleeve D', which is provided with a number 100 of teeth d³, arranged spirally around said sleeve, which are for the purpose of crushing the ears of corn and also for the purpose of conveying the crushed material to the burs at the open end of the cylinder. The sleeve D' 105 is preferably shrunk on the shaft B and has its end opposite that nearest the pulley H' provided with a recess d⁴ to receive a tongue

or projection d^5 on the collar D^2 , which is provided at proper points with spirally-formed blades d^6 , which join or complement similarly-formed blades d^7 on the sleeve D' , thus forming screw-blades. By reference to Fig. 3 of the drawings it will be seen that the collar D^2 is partially located within the cylinder D and partly within the opening f of the bur F , which is fixed on the open end of the cylinder.

10 Mounted on the shaft B , adjacent to the serrated surface of the bur F , is another bur G , which carries one or more cleaners or fingers g , which may be made integral with said bur or secured thereto on its periphery by any suitable means. The cleaners or fingers g may be provided with serrations or teeth g' to better engage the material which might collect between the outer portion of the bur F and the shell or casing G' , which incloses both burs

20 and which is provided with an opening in its lower portion for the passage of the ground material. The bur G is preferably secured by means of bolts g^2 to a collar g^3 , which is provided with a set-screw g^4 to adjustably secure it to the shaft B . Communicating with the opening in the lower portion of the shell G' is a chute c , which is connected at its other end to the boot of the elevator-casing C' of an elevator of the ordinary or well-known type, which

25 casing and elevator is employed to carry the crushed and ground material to a hopper I , which is located above the shaft C , on which is mounted a shell or casing L , within which casing are burs of the type just above described or of any other suitable construction, but which burs are formed with finer serrations and adjusted closer together than the first-named burs, so as to reduce the material to a finer powder or particles. The hopper I

30 communicates through a chute l with the upper portion of the shell or casing L , and the lower part of said casing is provided with a chute m , which communicates with the boot of an elevator-casing M , which is provided with elevators of the well-known type, and which casing and elevators convey the ground material through its upper end N to a bin or other suitable receptacle. (Not shown.) The elevators within the casings

35 C' and M are operated by means of chains or belts n passing over suitable sprocket-wheels n' on the shaft C and suitable wheels n^2 , fast on the elevator-shafts, which are journaled at the upper ends of said casing. The gear H ,

40 which is driven by the main shaft B , meshes with a gear H^3 , fixed on the shaft C , and thus imparts motion to said shaft.

45 From the foregoing and by reference to the drawings it will be seen and readily understood that by placing a quantity of ears of corn in the inclined hopper or trough E the same will be conveyed to the cylinder D , where it will be crushed by reason of the rotation of the driving-shaft, to which power

50 may be applied through the pulley H' and by means of the teeth d^8 on the sleeve D' , mounted on said shaft. The teeth d^8 being ar-

ranged spirally on said sleeve will force the crushed material toward the open end of the cylinder D , from whence it will be carried through the medium of the blades d^6 and d^7 to the cavity between the burs F and G , by means of which it will be ground. In thus grinding the material I have found that as it passes between the burs it sometimes collects at their peripheries and clogs or impedes the operation of the rotary bur. To prevent said clogging of the material, I provide the rotary bur with one or more cleaners or fingers g , which may be provided with the teeth g' . (Shown in Fig. 5 of the drawings, as before stated.) The ground material passes from the shell or casing G' to the boot of the elevator C' and is then carried up and into the hopper I and from thence passes through the chute l into the casing L , where it is more finely ground, after which it passes out into the boot of the elevator M and from thence is conveyed, by means of said elevator, to sacks, a bin, or other suitable receptacle. To adjust the bur G with respect to the bur F without removing the shell G' , it is only necessary to loosen the set-screw h^2 and turn the nut h' on the screw-threaded portion of the main or driving shaft in the proper direction, so as to draw the bur G toward the bur F or to separate it therefrom.

It is evident that shelled corn or small corn may be placed in the hopper I and ground, by means of the burs on the shaft C , without passing the same through the cylinder and other burs. It is further apparent that by mounting the various parts of the mill on one and the same main frame a complete machine in a compact and portable form is furnished.

Having thus fully described my invention, what I claim as new, and desire to secure by Letters Patent, is—

1. The combination with a shaft suitably journaled and having a screw-threaded portion provided with a series of indentations arranged spirally around the same, a stationary bur around the shaft, another bur adjustably mounted on the shaft near the first-named bur, a nut engaging the screw-threads, and a set-screw to engage the depressions in the shaft and to fix the nut thereon, substantially as described.

2. The combination with a casing, a bur fixed therein and having a peripheral recess and a central opening, a shaft passing through the latter, and means for crushing the material and feeding it axially through said opening; of a rotatable bur fixed on the shaft within said casing, and at its periphery longitudinally-projecting cleaners or fingers provided with serrations extending into and traveling around within said recess of the fixed bur, substantially as described.

ASHLEY C. SMITH.
